CLAIM(56) **References Cited**

(57) The ornamental design for a set of closures, as shown and described.

DESCRIPTION

U.S. PATENT DOCUMENTS

FIG. 1 is a top perspective view of a set of closures of the present design;

3,727,829 A	4/1973	Hüni
3,815,810 A	6/1974	Wellman
3,877,352 A *	4/1975	Brieske B65D 33/10 383/28
5,088,667 A *	2/1992	Olson B65F 1/1415 248/101
5,501,378 A *	3/1996	Kolton A47G 25/743 223/85
5,692,837 A	12/1997	Beer
6,047,883 A	4/2000	Calvert
6,082,897 A	7/2000	Galomb
D430,490 S *	9/2000	DuCorday D9/443
6,116,424 A *	9/2000	Leu B65D 33/001 206/554

FIG. 2 is a bottom perspective view of the design of FIG. 1; FIG. 3 is an end view of the design of FIG. 1 taken from the left-hand end of FIG. 2;

FIG. 4 is a side elevational view of the design of FIG. 1; FIG. 5 is a side elevational view of the design of FIG. 1 taken from the right-hand side of FIG. 2;

FIG. 6 is a top view of FIG. 1; and,

FIG. 7 is a bottom view of FIG. 1.

The broken lines in the drawings depict boundaries of the claim and form no part thereof.
